FIG. 1

FIG. 2

FIG. 6

FIG. 7

FIG. 3

FIG. 4

FIG. 5

FIG. 1 is a perspective view of a filter for aquariums and the like embodying our new design as seen from one of its duplicate ends;

FIG. 2 is a top plan view thereof;

FIG. 3 is a front elevation view thereof;

FIG. 4 is a rear elevation view thereof;

FIG. 5 is a bottom plan view thereof;

FIG. 6 is a fragmentary top plan view of a modified form of the filter for aquariums shown in FIG. 1; and

FIG. 7 is a rear elevation view of the filter of FIG. 6 on the reduced scale.

The broken line representation of an aquarium, the air manifold tube, the air lines and the air bubbles in FIG. 1 are for purposes of illustration only.

We claim:

The ornamental design for a filter for aquariums and the like, substantially as shown and described.
